UNITED STATES PATENT OFFICE

110,265

DESIGN FOR A BARREL FOR MECHANICAL PENCIL OR SIMILAR ARTICLE

Robert Back, Chicago, Ill., assignor to The Wahl
Company, Chicago, Ill., a corporation of Del-
aware

Application February 5, 1938, Serial No. 74,910

Term of patent 7 years

To all whom it may concern:

Be it known that I, Robert Back, a citizen of the United States, residing at Chicago, in the county of Cook and State of Illinois, have invented a new, original, and ornamental Design for a Barrel for Mechanical Pencil or Similar Article, of which the following is a specification, reference being had to the accompanying drawing, wherein the figure is an elevational view of a pencil barrel embodying my new design. The article has substantially the same aspect when viewed from any side.

The bands or rings indicated by the white areas between stippled areas are of a color con-

trasting with the adjacent areas on which the stippling appears.

The design constituting the subject matter of the invention may be embodied in a barrel for such articles as a pencil, fountain pen or combination fountain pen and pencil without departing from the scope of the invention as specified in the appended claim.

I claim:

The ornamental design for a barrel for mechanical pencil or similar article substantially as shown and described.

ROBERT BACK.
